DESIGN FOR A SWITCH PLATE

Ernest Bendorf, Conrad, Mont.

Application December 27, 1939, Serial No. 89,161

Term of patent 14 years

To all whom it may concern:

Be it known that I, Ernest Bendorf, a citizen of the United States, residing at Conrad, in the county of Pondera and State of Montana, have invented a new, original, and ornamental Design for a Switch Plate, of which the following is a specification, reference being had to the accompanying drawing, forming a part thereof.

Fig. 1 is a side elevational view of a switch plate showing my new design;

Fig. 2 is a front elevational view, and
Fig. 3 is an end elevational view.

I claim:

The ornamental design for a switch plate, as shown.

ERNEST BENDORF.
